UNITED STATES PATENT OFFICE.

WILLIAM HENRY BAUERT, OF ROSEVILLE, NEW SOUTH WALES, AUSTRALIA.

HAT-VENTILATION MEANS.

1,339,154.

Specification of Letters Patent.

Patented May 4, 1920.

Application filed September 23, 1918. Serial No. 255,400.

To all whom it may concern:

Be it known that I, WILLIAM HENRY BAUERT, a subject of the King of Great Britain and Ireland, etc., residing at Shirley 5 Road, Roseville, in the State of New South Wales, Commonwealth of Australia, have invented certain new and useful Improvements in Hat-Ventilation Means; and I do hereby declare the following to be a full, 10 clear, and exact description of the invention, such as will enable others skilled in the art to which it appertains to make and use the same.

Devices have been used to promote ventilation in hard hats—as the helmet, bowler, and some of straw—and soft ones—as alpines, other felts, and caps, but such devices are uncomfortably rigid, or they fail to permanently supply ample space for the 20 passage of air up and down between the wearer's head and the hat side into the space over the top of the head.

My invention is for soft hats chiefly because to most people no stiff hat is comfortable, especially in hot weather, and more especially when such persons perspire; and because I aim at uniting comfort with health by providing really permanent and ample air space to allow the air to pass up 30 the hat side to reach the space over the wearer's crown and to allow air from the latter space to pass down, so that the air in that space will be kept fresh. Small holes spaced apart in a hat are useless for 35 the purpose stated.

I provide according to the construction I prefer, an attachment or attachments inside the hat, with one or more leather, textile or other pliable sweat bands the softness, 40 moisture absorbent qualities, and general smoothness of such a band being excellent features. But as the commonly used sweat band becomes insanitary with perspiration, dust, and sometimes grease, before the hat 45 is discarded, and as it is usually so sewn in that it cannot be readily changed by the wearer for a clean one I provide means whereby the said change will be easy.

I use one or more flexible resilient or 50 springy corrugated or other strips, of any suitable cross section and material or combination of materials, such as metal, celluloid, composition or so on, plain or having a covering as of textile.

If bare metal is used it will be sufficiently

rust proof to withstand perspiration and damp.

Each strip or series of strips is shaped in curved form to fit inside the curve of the hat side as a sweat band fits, and is also 60 bent or curved to have an outer and an inner side, these sides being spaced well apart to leave ample room between them for upward and downward passage of air.

When the material of the strip is not of 65 round cross section it might be called a ribbon but as the material used will be in most cases light wire of round cross section I will in this specification call all the said 70 springy strip material which provides the said air spaces, wire.

Owing to its flexibility and resilience my wire when in the hat will afford a comfortable fit, and it will be able to expand somewhat under very moderate internal pressure 75 and thus could fit heads which differed a little in size.

The above and other details of the invention will now be described with reference to the accompanying drawings, which are 80 diagrammatic. Although flat leather sweat bands are illustrated other current styles are usable. In the drawings Figure 1 is a sectional view through the side of the hat, to which is attached one form of my wire 85 attachment with a sweat band as of leather added. The dotted line represents part of the wearer's head, and arrows show where air can pass freely up and down between that line and the inside of the hat. Fig. 2 90 is a sectional view through a hat side with an attached housing or keeper for tips or other parts of a wire or wires of the kinds shown for example in Fig. 6.

Fig. 3 shows an end section of a ventilating wire modified so as to have a leather sweat band or the like at each side, so that when the band on the head side becomes soiled the fitting shown may be reversed in position to bring the clean band next to the 100 head. Fig. 4 is a section through the form of the device shown in Fig. 2, with the spring in place, and sweat band secured to the spring. Fig. 5 is a view of part of a hat side from within with parts of a leather sweat 105 band and between it and the hat a ventilating wire attached. Fig. 6 is on a smaller scale and shows a hat under side with various arrangements of my fittings. In these views 1 is the hat crown outer side, 2 the hat brim, 110

3 its ribbon, 4 part of the wearer's head, 5 a housing for one or more of my ventilating wires (to hold in place their ends or an intermediate part of any such wire) and 5^a is any means connecting the housing to the hat. 6 is any means connecting to the hat the ventilation wire 7; and 8, 8^a indicate absorbent flexible sweat bands. 7^a is one of the modified forms of the ventilating 10 wire—obviously usable, and 9 and 11 are air spaces of ample width between the inner (or head) and the outer (or hat) sides of the ventilating wire. 10 is the space in housing 5 to receive and locate the ends of 15 adjoining ventilating wires, or to locate an intermediate part of any one wire, and 12 is any suitable connection to be used between a sweat band 8 and a ventilating wire 7, or 7^a.
 20 One ventilating wire 7, may extend all around the hat side inner surface 13. If its ends be not socketed in a housing; they are connected in any other suitable manner for example as ends of spring wire in armlets 25 are connected.

In my preferred construction a plurality of housings are attached to the hat surface 13 so that my ventilating wire or series of wires, can be attached or be removed without any trouble. There is in some cases a top and a bottom wire 15 running around like a ring inside the ventilating wire or wires and adapted to be sewn or attached to the hat side. Even when the connection is by 30 sewing the stitches do not need to be all around part 13 but at intervals only, so that the labor of renovation is reduced.

In the example in Fig. 5, downward and upward extensions of the wire are oblique, 40 but the shapings of the wire may be varied while retaining stated advantages. An absorbent band is shown at 8^b in Fig. 6 on the head side of the ventilating wire; another band at 8^c is shown laced in and out of the 45 wire. And at 8^a a band is shown located wholly inside the air space 9, without filling that space.

When a plurality of ventilating wires is used to form a circuit there will be in some 50 cases gaps 14 between their ends.

The air space 9, 11 or the like will diminish to some extent readily when pressure is put on the leather sweat band or on the ventilating wire or wires in the use of 55 the hat, but it will be impossible by any normal pressure to obliterate the space 9 provided for air passage or to so reduce it as to destroy the efficiency claimed for this invention. It will be impossible for the head of 60 the wearer to come so close to surface 13 that ample fresh air is prevented from ris-

ing or heated air is prevented from descending between the sweat band and the wall of the hat.

If there be holes in the upper part of the 65 hat crown air will also escape through them. The ventilating wire or wires will accommodate themselves to the shape of the wearer's head, and though they will in many cases under continued wear take a shape 70 more closely fitting the wearer's head than originally, other more temporary stresses on the wires will not prevent the normal or correct shape being regained by the ventilating wire when such stresses are removed. 75

In practice the parts used will have any suitable dimensions but in my preferred construction the leather or absorbent sweat band extends a little higher and a little 80 lower than the ventilating wire or wires. 80

Having described this invention what is claimed by Letters Patent is:—

1. The combination with the crown of a hat, of a housing secured therein and extending thereabout and having an approximate U-shape in cross-section, said housing having its edges bent to provide inwardly projecting overhanging flanges, a hollow ventilator spring having spaced side members providing an air space therebetween, 85 said spring being removably mounted in the housing, and an absorbent member secured to the inner side of the spring.

2. The combination with the crown of a hat, of a housing secured therein and extending thereabout and having its edges bent into U-shaped flanges, there being a space between the ends of the flanges which is arranged innermost, a hollow ventilator 95 spring having spaced side members providing an air space therebetween, said spring being removably mounted in the housing and adapted to be passed through said space, upper and lower wires arranged within the hollow ventilator spring, and an absorbent 100 member secured to the inner side of the 105 spring.

3. The combination with the crown of a hat, of a head surrounding hollow ventilator element arranged therein, said ventilator 110 element being formed of a section of wire bent into a plurality of upstanding turns, said turns including upper and lower substantially horizontal transverse elements and inner and outer approximately vertical 115 elements connecting the transverse elements, the transverse elements being horizontally spaced and the approximately vertical elements being spaced laterally.

In witness whereof I have hereunto set my hand.

WILLIAM HENRY BAUERT.
